UNITED STATES PATENT OFFICE.

MOSES M. RIGLANDER, OF NEW YORK, N. Y., ASSIGNOR TO HAMMEL RIGLANDER & CO.,
OF NEW YORK, N. Y., A CORPORATION OF NEW YORK.

DESIGN FOR AN ENGRAVER'S BLOCK.

43,233.

Specification for Design.

Patented Nov. 5, 1912.

Application filed July 12, 1912. Serial No. 709,071. Term of patent 14 years.

To all whom it may concern:

Be it known that I, MOSES M. RIGLANDER, a citizen of the United States, and a resident of the city of New York, county of New York, and State of New York, whose post-office address is 49 Maiden Lane, in said city, have invented a new, original, and ornamental Design for an Engraver's Block, of which the following is a specification.

Reference is had to the accompanying drawing, forming part thereof, in which—

Figure 1 is a perspective view of the engraver's block. Fig. 2 is a plan view of the same.

I claim:

The ornamental design for an engraver's block, as shown.

MOSES M. RIGLANDER.

Witnesses:

GUSTAVE I. ARONOW,
H. RADZINSKY.
